UNITED STATES PATENT OFFICE.

PETER N. NYHOLM, OF EDGEWOOD, WASHINGTON.

EXTENSION-TABLE.

1,302,420.

Specification of Letters Patent. Patented Apr. 29, 1919.

Application filed February 8, 1917. Serial No. 147,360.

To all whom it may concern:

Be it known that I, PETER N. NYHOLM, a citizen of the United States, residing at Edgewood, in the county of Pierce, State 5 of Washington, have invented certain new and useful Improvements in Extension-Tables, of which the following is a specification.

This invention relates to tables such as 10 are ordinarily known as dining tables and especially to that class thereof adapted to be extended by the separation of the end portions and the insertion therebetween of one or more intermediate leaves.

15 The objects of the invention are to provide means for operating the two end portions whereby they may be separated or drawn together by turning a crank; means whereby said parts may be locked in such 20 position so that the extended table may be freely moved without the said parts pulling apart when under the strain of being moved; means for storing the intermediate leaves within the table; and means whereby 25 said leaves may be inserted in place with ease from one side of the table. The invention further consists in certain improvements in the construction of the table, and its leaves, whereby it is thoroughly practical 30 and convenient, and yet does not represent any substantial increase in expense.

I attain these and other objects by the devices, mechanisms, and arrangements illustrated in the accompanying drawings, 35 in which—

Figure 1 is a plan view of my improved table in closed position, a part of the top being broken away to reveal the interior thereof;

40 Fig. 2 is a cross-section thereof;

Fig. 3 is a plan thereof in extended position;

Fig. 4 is a cross-section of a part thereof, showing the leaves being removed from the 45 interior thereof;

Fig. 5 is a section of a portion of the table top showing the leaf-supporting-bar guide;

Fig. 6 is a perspective view thereof;

50 Figs. 7, 8 and 9 are views showing the leaf engaging the supporting bar and, respectively, in positions before it is unfolded, while unfolding, and after it is unfolded and is in position for use;

55 Fig. 10 is a section of a part of the leaf and its folding apron;

Figs. 11 and 12 are views of the operating drum showing it in locked and unlocked or operating positions, respectively.

Similar numerals of reference refer to 60 similar parts throughout the several views.

The table illustrated in the drawings is provided with a central leg 1 and a split hollow pedestal 2 surrounding said leg when the table is in closed position. The central 65

leg 1 supports a central cross-bar 3 above it, and each half of the pedestal 2 supports a similar cross-bar 4. These three bars 3 and 4 support the entire table top by means of two sets of sliding bars. Each such set of 70 sliding bars consists of one inside bar 5 secured to one section 6 of the fixed table top and to one of the cross-bars 4, an adjacent central bar 7 secured at its center to the central cross-bar 3, and a third adjacent 75 outside bar 8 secured to the other section 9 of the fixed table top and to the other cross-bar 4. These bars 5, 7 and 8 are fastened together in such manner that they permit a relative longitudinal sliding motion past each other in the usual way. Referring particularly to Fig. 1, it will be observed that a drum 10 is mounted under the table top 6 and is provided with two cables 11 and 12 secured thereto and wound thereon. The two ends of the cable 11 pass toward the right from the said drum while the cable 12 passes to the left therefrom. One end of each cable passes over suitable 80 guide pulleys from the drum 10 and is fastened to the outside sliding bar 8 at 13 while the other end passes over other guide pulleys along the inner sliding bar 5 and around a pulley mounted on the far end of said bar 5, thence back between the sliding 85 bars 5 and 7 to and around a pulley mounted on the near end of said central bar 7, thence back again between said bars 5 and 90 7 and around a pulley mounted on the far end of said bar 7, thence between the bars 100 7 and 8 and secured to said bar 8 at a point 14 adjacent its near end. Thus when the parts are in the closed position (Fig. 1) and the drum 10 is rotated in counterclockwise direction the ends of the cables secured to 105 the outer bars 8 at 14 are pulled so that the bars 8 slide away on the central bars 7 and the inner bars 5 slide forward on said bars 7, thus separating the cross-bars 3 and 4 and the table tops 6 and 9 (Fig. 3). Similarly the reverse motion of the drum 10 slackens the above-mentioned cable end and

tightens the other end thus drawing the bars 8 and the top 9 forward and the bars 5 and the top 6 rearward, thus closing the table tops together.

- 5 Referring now to Figs. 11 and 12 showing the details of said drum and its operating and locking mechanisms. The drum is mounted on a rotatable pipe or hollow shaft 15 suitably supported below the table 10 top 6 adjacent the apron 16. A ratchet 17 is slidably mounted in the end of the drum 10, having its teeth projecting sidewise so as to engage the staple or other tooth 18 in the inner face of the apron 16. This ratchet 15 is pressed outward by a spring 19 thus bringing its teeth into such engagement with the tooth 18. A pin 20 is secured to the ratchet and passes through or across the shaft 15 through a suitable elongated slot 21 therein. The operating handle 22 is adapted to be inserted in the open end of the shaft 15 and is bifurcated at its end so as to span the said pin 20. The end of the slot 23 forming said bifurcation is 25 adapted to engage the said pin 20 and to push it laterally in the slot 21 so as to remove the teeth of the ratchet 17 away from the tooth 18 and thus unlock the said drum 10. The drum may then be turned in either 30 direction by rotating the handle. A spring latch 24, having beveled sides, is also mounted in the drum 10 and passes inward through a hole in the shaft 15 and is adapted to engage one of two notches 25 in the 35 end of the handle 22 when it is in such position as to unlock the drum, as above described, and to hold it in such place in the drum until it is desired to remove it thus again lock the drum. It is evident from 40 the above that the table may be opened or closed by turning the handle and that as soon as the handle is removed the table parts are locked together since the drum cannot be turned.
- 45 Referring now to Figs. 1, 2, 3 and 4 it will be observed that a pair of strips 26 are mounted immediately above the cross-bars 3 and 4, one said strip being secured to each of said bars 4 and extending past 50 the other over the central cross-bar 3. These strips form a support for one end of the folded intermediate leaves when they are not in use. The other end of the folded leaves is supported by a half-round bar 27 55 which is hung from the under side of the two top sections 6 and 9. The bar 27 has an upward extending foot or hanger 28 formed at each end, said foot being slidably supported by a guide piece 29 secured to the 60 said top sections 6 and 9. Said hanger

28 passes through a slot 30 in said guide piece 29 so that, as the sections 6 and 9 are slid apart, the bar 27 remains to span the space between them. The bar 27 is of sufficient length to carry all the extra leaves of the 65 table. The leaves are supported from said bar 27 by means of a strap 31 secured to their lower sides (when unfolded) as hereinafter described.

Each leaf is divided transversely into two 70 equal parts 32 and 33, and said parts are fastened together at their dividing line by suitable hinges 34 (Figs. 7, 8 and 9). One end of each strap 31 is secured to the under side (unfolded, Fig. 9) of the part 33 and 75 extends therefrom to a point adjacent the center of said part 33. The half-round bar 27 passes between said strap 31 and the part 33 of the leaf, said bar engaging said central end of the strap when the leaf is folded 80 away (Figs. 1 and 2). When the ends of the parts 32 and 33 are lifted up and pulled forward (Fig. 4) the strap 31 slides on the bar 27 until it reaches its end (Fig. 7). A stop 35 is secured to the part 33, adjacent the end of the strap 31, said stop having a notch 36 adapted to fit the half-round bar 27, so that when the end of the part 32 is raised, after it has been drawn forward, it will be prevented from sliding on the bar 90 27 (Fig. 8) and so that when the said part is completely opened out the end now forming the center of the unfolded leaf will be supported (Fig. 9). The aprons 38 on the 95 ends of the leaves are hinged to the respective parts 32 and 33 and are preferably provided with light springs 37 (Fig. 10) to insure that they assume a vertical position to register with the aprons 16 of the table tops 6 and 9.

Having described my invention, what I claim is:

In an extension table, the combination with two permanent top sections, of a table leaf supporting bar suspended from the 105 under face of said sections, a leaf divided transversely with its parts hinged together, a strap secured at its ends to and with its intermediate portion spaced from the under face of one of the sections of the said leaf, 110 the said bar being slidably mounted between the underface of the leaf and the said strap, a stop secured at one end of said strap between the strap and table leaf, a notch in said stop adapted to receive said supporting 115 bar, said supporting bar functioning to support the table leaf in its extended and folded positions.

PETER N. NYHOLM.
